Primary Examiner — Mark A Goodwin*Assistant Examiner* — Adam C Mager(74) *Attorney, Agent, or Firm* — Baker Botts L.L.P.(57) **CLAIM**

The ornamental design for a micro-mobility transit vehicle, as shown and described.

DESCRIPTION

FIG. 1 is a rear, left, and top perspective view of the micro-mobility transit vehicle embodying the new design; FIG. 2 is a front, right, and bottom perspective view thereof; FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The evenly dashed lines are shown for the purpose of illustrating portions of the micro-mobility transit vehicle and form no part of the claimed design.

1 Claim, 8 Drawing Sheets(56)
